UNITED STATES PATENT OFFICE.

EDWARD MURRAY, OF DETROIT, MICHIGAN.

ADJUSTABLE WINDOW-SHADE FIXTURE AND CURTAIN-POLE BRACKET.

1,238,931.

Specification of Letters Patent.

Patented Sept. 4, 1917.

Application filed November 2, 1916. Serial No. 129,043.

To all whom it may concern:

Be it known that I, EDWARD MURRAY, citizen of the United States, residing at Detroit, county of Wayne, State of Michigan, have invented a certain new and useful Improvement in Adjustable Window-Shade Fixtures and Curtain-Pole Brackets, and declare the following to be a full, clear, and exact description of the same, such as will enable others skilled in the art to which it pertains to make and use the same, reference being had to the accompanying drawings, which form a part of this specification.

My invention relates to an adjustable window shade fixture and curtain pole bracket shown in the accompanying drawings and more particularly pointed out in the following specification and claims.

One of the objects of the present invention is to provide a device simple and inexpensive in construction and operation and which may be readily attached to a window casing.

Another object of the invention is to provide for attaching the device to the opposing walls of a window casing instead of its outer face, thus relieving the more exposed face of the window casing of holes or an otherwise marred appearance, as a result of the removal of the fixture.

Another object of the invention is to provide for the adjustment of the brackets supporting the curtain roller that the latter may be removed from one window casing and installed on casings of varying width upon the adjustment of the bracket in the slotted way of the supporting fixture.

Another feature of the invention is to provide for the ready removal of the curtain pole bracket from engagement with the fixture supporting the roller bracket.

Another object is to provide for automatically locking the curtain pole bracket when assembled with the supporting fixture, that the parts may be secured against accidental dislodgment.

Another feature of the invention is that it may be readily constructed of sheet metal by suitable dies, thus materially reducing the cost of manufacture.

Other advantages and improvements will hereafter appear as the description proceeds, the invention residing in the combination and arrangement of parts and details of construction hereinafter described and claimed, it being understood that changes

may be made in the precise embodiment of the device herein disclosed without departing from the spirit of my invention.

In the accompanying drawings forming 60 part of this specification:—

Figure 1 is a perspective view of a sheet metal blank of the fixture for supporting the adjustable curtain roller bracket, and also the curtain pole bracket. 65

Fig. 2 is a perspective view of the supporting fixture as it would appear when finished.

Fig. 3 is a perspective view of the adjustable curtain roller bracket and connecting 70 parts.

Fig. 4, is a perspective view of the curtain pole bracket.

Fig. 5, is a perspective view of the device with the several parts in assembled 75 relation.

Fig. 6 is a cross-sectional view on line 6—6 looking toward the curtain roller bracket.

Referring now to the letters of reference 80 placed upon the drawings.

A, denotes a bracket supporting fixture preferably formed of sheet metal having one end A', bent at right angles to its body portion, which is provided with an elongated slot A². B, is a curtain roller bracket which may be also formed of sheet metal, having a flange B', provided with an opening b, for the passage of a bolt C, extending from the back through the elongated 90 slot A², of the fixture. C', is a milled nut fitted to the bolt to secure the bracket to the fixture when properly adjusted. The margin surrounding the slotted opening in the fixture is preferably recessed as indicated at a, to receive a co-acting projecting portion b', formed in the flange of the bracket to insure the bracket against accidental rotative displacement when adjusted. 95

D, is a curtain pole bracket having an arm 100 d, journaled in a bearing A³, projecting above the upper edge of the supporting fixture.

The bearing A³, is provided with a groove or ridge portion a', to admit the lug d' on 105 the end of the arm d, of the curtain pole bracket;—a portion of the bearing being cut away as indicated at a² to permit the arm of the bracket D to rock slightly in the bearing that the lug d' may overlap the edge of the 110 ridge wall a', and bear upon the supporting fixture to support the bracket in proper

position and against accidental dislodgment when assembled.

Having indicated the several parts by reference letters the construction and operation of the device will be readily understood. A pair of bracket supporting fixtures are first secured to the opposing walls of the window casing and the shade roller brackets adjusted in the elongated slot of the fixtures to accommodate the fittings on the end of the roller. The curtain pole brackets are then mounted in the bearings provided in each fixture, the lug on the bracket arm engaging the edge of the bearing to secure the bracket against accidental release as previously explained.

Having thus described my invention what I claim is:—

1. In a bracket supporting fixture, a body portion having a bearing formed thereon, a curtain pole bracket having a journal arm for engagement with said bearing, and means carried by the journal arm to prevent accidental disengagement of said journal arm from said bearing.
2. In a device of the character described, a bracket supporting fixture comprising a body portion, said body portion being provided with an integral lateral extension bent to form a bearing, and a curtain pole bracket having a journal arm to engage in said bear-

ing, and means carried by the journal arm for engagement with said bearing to prevent accidental disengagement of said journal arm from said bearing.

3. In a bracket supporting fixture, a body portion having a bearing formed thereon, said bearing having a longitudinal groove opening into one side thereof, a curtain pole bracket having a journal arm adapted to fit in said bearing, and a lug on said journal arm adapted to engage with said groove to prevent accidental disengagement of said journal arm.

4. In a bracket supporting device, a body portion having a bearing formed thereon, said bearing having a longitudinal groove opening into one side thereof and terminating short of one end of said bearing, said end of said bearing being provided with a notch, a curtain pole bracket having a journal arm adapted to fit in said bearing, and a lug on said journal arm adapted to engage with the end of said groove and the notch to prevent accidental disengagement of said journal arm.

In testimony whereof, I sign this specification in the presence of two witnesses.

EDWARD MURRAY.
